MATCHBOOK HOLDER

Lawrence M. Spicer, San Francisco, Calif., assignor of forty-five per cent to George Sikol, San Francisco, Calif.

Application February 15, 1941, Serial No. 379,130

2 Claims. (Cl. 206—38)

The present invention relates to holders for match books and other articles and has for its primary object to provide a flexible case formed of leather, fabric, or other foldable material having pockets therein adapted for receiving a book of matches as well as for holding a mirror, personal cards, or the like, and in which the case is adapted to be folded along a transverse medial line into a closed position.

A further important object of the present invention is to provide a pocket in the case within which the book of matches is adapted for positioning and provided with an opening in the pocket to expose the match striking portion of the book of matches to enable the striking of the matches thereon without removing the match book from the case.

A still further object is to provide a device of this character of simple and practical construction, which is neat and attractive in appearance, relatively inexpensive to manufacture and otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which—

Figure 1 is a front elevational view showing the holder in closed position,

Figure 2 is a side elevational view thereof,

Figure 3 is a front elevational view showing the holder in an open position,

Figure 4 is a longitudinal sectional view taken substantially on a line 4—4 of Figure 3,

Figures 5 and 6 are transverse sectional views taken respectively on the lines 5—5 and 6—6 of Figure 3,

Figure 7 is a fragmentary plan view of one end of the holder showing the manner in which the side flaps are folded inwardly adjacent the closure flap,

Figure 8 is a plan view of the blank from which the holder is constructed, and

Figure 9 is a perspective view of one of the mirror retaining straps.

Referring now to the drawings in detail, wherein for the purpose of illustration I have disclosed a preferred embodiment of the invention and with particular reference to Figure 8 of the drawings, the numeral 5 designates the blank sheet of leather, fabric, or other material from which the holder is constructed, the blank being of substantially rectangular form and provided

with flaps 6—6 at its longitudinal edges adapted for folding inwardly along the fold lines designated at 7. At one end of the blank is a flap 8 adapted for folding along a transversely extending fold line 9 to form a closure flap and at the opposite end of the blank is a flap 10 adapted for folding along a transversely extending fold line 11 to provide a pocket designated at 12 in Figure 4 of the drawings to receive a book of matches 13. The flaps 6 and 10 are secured in position by stitching 14.

The flap 10 forming the pocket 12 is provided with an opening 15 for exposing the match striking strip 16 usually provided at the bottom edge of the book of matches.

The stitching 14 also serves to secure a transversely extending flexible strip 16 to the inside of the holder adjacent the fold line 9. The strip 16 forms a pocket within which a mirror 20 or similar article may be positioned under the strips 16 and 18.

It will be apparent that the holder may be folded along its transverse medial line 17 to enclose the book of matches 13 as well as the mirror 20 and the flap 8 may then be folded over the bottom end of the holder and secured in position by means of a snap fastener 21.

It is believed the details of construction, advantages and manner of use of the device will be readily understood from the foregoing without further detailed explanation.

What I claim is—

1. A match book holder comprising a blank sheet of flexible material of substantially rectangular form, an inwardly folded flap at the longitudinal edges of the blank, an inwardly folded flap at one end of the blank, spaced parallel transverse strips adjacent the other end of the blank, longitudinally extending rows of stitching securing said flaps and strips to the blank, the intermediate portion of said strips being free for receiving a flat article behind the strips and inwardly of the edges of said longitudinal flaps said end flap having its central portion free to provide a pocket adapted to removably receive a match book also inwardly of the edges of the longitudinal flaps, said end flap having an opening for exposing the match striking abrasive carried by the match book, said blank being folded upon itself at an intermediate transverse portion and a closure flap for securing the holder in folded position.

2. A match book holder comprising a blank sheet of flexible material of substantially rectangular form adapted for folding along a trans-

versely extending line to provide a pair of foldable sections, an inwardly folded flap at the longitudinal edges of each section, an inwardly folded flap at the end of one section to form a pocket, a pair of spaced apart flexible strips extending transversely of the other section, longitudinally extending rows of stitching securing the first named flaps and the side edges of the end flap as well as the ends of the strips to the respective sections, said pocket being adapted to receive a match book therein inwardly of the

edges of the longitudinal flaps and having an opening exposing the match striking abrasive carried by the match book, one of said strips forming a pocket adapted to receive a flat object positioned behind the strips also inwardly of the edges of the longitudinal flaps, and a closure flap at the end of the section remote from the match book to secure the sections in folded position.

LAWRENCE M. SPICER.
